UNITED STATES PATENT OFFICE

1,989,798

BUILDING SLAB AND WALL CONSTRUCTION

Thomas J. Foster, Ridgewood, N. J.

Original application September 24, 1927, Serial No. 221,780, now Patent No. 1,825,346, dated September 29, 1931. Divided and this application January 29, 1931, Serial No. 512,116

11 Claims. (Cl. 72—16)

This application is a division of my copending application Serial No. 221,780, filed September 24, 1927, (Patent No. 1,825,346, issued September 29, 1931) and the invention herein described and claimed relates to materials for building construction, and is particularly applicable to the construction of floors, ceilings, roofs, walls and partitions, where non-combustibility and sound proofness combined with light weight are desirable.

The invention aims to provide a light, strong, heat and sound proof fire-resisting slab which may be put in place with facility and does not require plastering to make an acceptable finish.

Further objects of the invention appear hereinafter in connection with the description of the several embodiments illustrated in the accompanying drawings, wherein

Fig. 1 is a perspective view of a wall embodying the invention, showing the various steps or stages in erection;

Fig. 2 is a cross-section through a ceiling slab at right angles to the direction of the reinforcing strips, showing several varieties of reinforcing and nailing strips suitable for supporting a floor having a wood finish;

Fig. 3 is a similar view of a roof slab having a cement or composition finish;

Fig. 4 is a horizontal cross-section through an outside wall embodying the invention showing a preferred form of stud construction;

Figs. 5 and 6 are similar views illustrating other forms of stud construction; and

Fig. 7 is a perspective view of a supporting sheet and stiffening bars ready to be placed in a horizontal supporting frame and receive the aerated gypsum or similar plastic material to form a slab.

This invention is illustrated in Fig. 1 as applied to an inside wall supported upon floors carried by light weight beams 11, the floor slabs 12 being composed of heat and sound insulating material from two to three inches or more in thickness and provided with wood screws or nailing strips 13 for a wood floor 14, as is customary in apartments and offices and other buildings having this type of floor. Any type of floor construction may be used with partition walls embodying the invention, as it is adapted to both fire proof and semi-fire proof or fire resisting construction.

In the floor illustrated, the floor slab 12 is composed of suitable fire resisting sheets or boards 15, such as sheet rock, gypsum boards, etc., commonly used for partitions and ceilings, which

are laid across the supporting beams 11 and insulate them from the floor slab as described in my Patents Nos. 1,582,172 and 1,582,173, dated April 27, 1926, and which in turn support the floor filling 16 of light weight heat and sound insulating material, as described in my Patent No. 1,717,444 dated June 18, 1929.

The floor supporting sheets 15 are preferably stiffened to give them sufficient strength and rigidity to support the filling 16 during construction by ribs or bars 17, of wood or metal, which are secured flat against the floor sheets for their entire length by means of suitable adhesive 18, such as asphaltum or other sticky non-combustible material, that retains its adhesive properties for an indefinite period. These bars 17 may be made the full depth of the fill and used to support the floor finish 14 in wooden floors, or they may be shallower and covered by the fill, as desired. Composite ribs 19 of wood and metal may be used to advantage, as illustrated in Fig. 2.

Fastening the strengthening ribs to the sheets in the manner described stops the vibration in the ribs so that sound will not be conducted through them, thereby eliminating any direct means for conducting sounds from the room above to the room below or vice versa.

Any suitable means for protecting the beams may be attached to the under side of the floor. For example, as shown in Fig. 1, the beam protection is afforded by cast concrete channels 20, which may be secured to the under side of the floor slab 12 by means of metal straps or hangers 21 embedded in the channels and having their upper ends projecting through the sheets 15 and anchored by any suitable means.

The wall slabs or "filling-in" panels 22 (see Figs. 1 and 4) are held at top and bottom by soffit boards 23, which may be secured beneath the beam covering by means of hangers or screws 24, and sills or plates 25, which may be laid along the floor upon the nailing strips where it is desired to erect a partition. The sills 25 are advantageously secured in position upon the nailing strips 13 or floor slab 12 by means of asphalt or other adhesive.

The wall slabs 22 preferably are precast or made up in advance and stored to harden and dry out thoroughly before being erected in their places in the structure, particularly if made of a wet material like cellular gypsum. In the form illustrated they comprise outer layers 26 of plaster board, sheet rock, or the like, between which is a filling 27 of cellular gypsum, or other heat and sound insulating material. The edges of the

slabs are formed of strips of wood 28, 29 or other suitable material having sufficient rigidity to maintain their form before being embedded in the filling, which may project slightly beyond the sheets to enable them to be secured to each other and to the soffit strips and sills by nails, screws, or other fastening means. The spaces 30 left between the edges of adjacent panels may be filled with putty or plaster to form a smooth wall (see Figs. 1 and 4).

The side edge stiffening strips 28 may be halved together or so shaped on their outer edges as to fit tightly against the outer edges of similar strips on adjoining slabs in the structure, as illustrated in Figs. 1 and 6, or they may be grooved and provided with tongues 31, as illustrated in Figs. 4 and 5, or otherwise shaped and secured together. Intermediate stiffening strips 32 (see Fig. 7) may be provided if the slabs are not sufficiently rigid without.

For exterior walls and roofs, a layer of waterproofing 33 may be applied on the outer side of the filling, and if desired, a layer of wire mesh reinforcement 34 may be embedded therein to give additional strength. Stucco or other finishing material 35 may be applied over the waterproofing for improving the external appearance of the structure, as illustrated in Fig. 4. A layer of chicken wire or wire mesh 36 to which the stucco is applied in the usual manner may be advantageously used to prevent exterior cracks if stucco or other weak material be used for the finish coat.

Various means for securing the assembled slabs in position may be used, depending upon the type of building. For example, the upper edges may be secured by corner molding 37, or may be embraced by the side walls of an inverted channel shaped ceiling finishing bead not illustrated. Adjacent slabs may be secured by screws, nails or both, passing through the abutting strips in addition to the grooves and splines 31. Whether the slabs be intended for partitions, sloping walls or roofs, or ceilings, will usually determine the nature of the securing means adopted for preventing displacement. The adaptability of the slabs to different types of construction is a characteristic feature of the invention.

A convenient method of constructing such slabs is illustrated in Fig. 7, wherein the side strips 28 and end strips 29 are shown as secured in place upon the edges of the supporting sheet 15 by any suitable means, and interior ribs or bars 32 are secured across the width of the sheet in one or more places. The corners may be strengthened with corner braces 39 if desired, which are likewise secured to the sheets 15. Asphaltum or other adhesive may be used for securing the strips and bars to the sheets. The sheet 15 and assembled side strips and stiffening bars are placed in the horizontal supporting frame 40, and poured full of plastic material level with the tops of the side strips. It will be understood that a second sheet may be laid on top of the plastic material and secured in place against the side strips to constitute a double faced slab, if desired.

The bars 41 in the bottom of the supporting frame enable the slab to be lifted out readily and carried to some suitable drying shed or rack, where it is left until the plastic material has hardened sufficiently to permit it to be erected in the building.

The slabs should be kept dry during the construction of the building, and this may be accomplished by covering them with a waterproof-

ing sufficient to exclude the moisture from them for some weeks. This cheapens the cost of the building by allowing floors and roof to be laid without waiting for wet slabs to dry out, and improves the construction by insuring that the floor finish and finished roof be put on dry slabs. Otherwise, moisture would have difficulty in getting out of the slabs after the floor waterproofing, roofing felt and finished roof was put on.

It is obvious that the invention may be embodied in various types of construction and utilize a wide variety of constructional materials, and that various modes of procedure may be followed in constructing the slabs and erecting the structure. The invention is not restricted to the illustrative embodiments shown and described.

I claim the following as my invention:

1. A substantially rigid heat and sound proof light-weight "filling-in" panel for attachment to a supporting frame in the construction of walls, partitions or roofs, consisting of a preformed slab comprising sheet-like insulating material having its edges secured to and stiffened by strips of rigid material, and a filling of light weight plastic heat and sound insulating material enclosed by said strips.

2. A substantially rigid heat and sound proof light-weight "filling-in" panel for attachment to a supporting frame in the construction of walls, partitions or roofs, consisting of a preformed slab comprising sheet-like insulating material stiffened by ribs secured thereto and having its edges secured to and stiffened by strips of rigid material, and a filling of light weight plastic heat and sound insulating material enclosed by said strips and embedding said ribs.

3. A substantially rigid heat and sound proof light-weight "filling-in" panel for attachment to a supporting frame in the construction of walls, partitions or roofs, consisting of a preformed slab comprising sheets of insulating material secured at their edges to the opposite sides of stiffening strips of rigid material, and a filling of light weight plastic heat and sound insulating material enclosed by said strips and filling the space between said sheets.

4. A substantially rigid heat and sound proof light-weight "filling-in" panel for attachment to a supporting frame in the construction of walls, partitions or roofs, consisting of a preformed slab comprising sheets of insulating material secured at their edges to the opposite sides of stiffening strips of rigid material, stiffening ribs secured to said sheets on the inner faces thereof, and a filling of light weight plastic heat and sound insulating material enclosed by said strips and filling the space between said sheets to embed said ribs.

5. A substantially rigid heat and sound proof light-weight "filling-in" panel for attachment to a supporting frame in the construction of walls, partitions or roofs, consisting of a preformed slab comprising sheets of insulating material secured at their edges to the opposite sides of stiffening strips of rigid material, and a filling of light weight plastic heat and sound insulating material enclosed by said strips and filling the space between said sheets, the outer side edges of said strips being shaped or adapted for engagement with similar shaped or adapted side edges of adjoining slabs in the structure.

6. A substantially rigid heat and sound proof light-weight "filling-in" panel for attachment to a supporting frame in the construction of walls, partitions or roofs, constituted by a slab having facing sheets of insulating material secured at

their edges to the opposite sides of stiffening strips of rigid material, and a filling of light weight plastic heat and sound insulating material enclosed by said strips and filling the space between said sheets, the outer side edges of said strips projecting beyond the edges of said facing sheets and being shaped or adapted for engagement with similar shaped or adapted side edges of adjoining slabs in the structure to form putty receiving open joints.

7. A substantially rigid heat and sound proof light-weight "filling-in" panel for attachment to a supporting frame in the construction of walls, partitions or roofs, consisting of a preformed slab comprising sheet-like insulating material having all its edges secured to and stiffened by strips of rigid material forming with said sheet like material a shallow box-like structure substantially closed except at the side opposite said sheet-like material, and a filling of light weight plastic heat and sound insulating material embraced by said sheet-like material and said strips and filling the box-like structure formed thereby substantially flush with the tops of said strips.

8. A substantially rigid heat and sound proof light-weight "filling-in" panel for attachment to a supporting frame in the construction of walls, partitions or roofs, consisting of a preformed slab comprising facing sheets of insulating material secured at their edges to the opposite sides of stiffening strips of rigid material forming with said sheets of insulating material a shallow box-like structure substantially closed on all sides, and a filling of light weight plastic heat and sound insulating material entirely filling the space within said shallow box-like structure.

9. A substantially rigid heat and sound proof light-weight "filling-in" panel for attachment to a supporting frame in the construction of walls, partitions or roofs, consisting of a preformed slab comprising a sheet of facing material having its edges secured to and stiffened by strips of rigid material, and a filling of light weight plastic heat and sound insulating material filling the space enclosed by said strips.

10. A substantially rigid heat and sound proof light-weight "filling-in" panel for attachment to a supporting frame in the construction of walls, partitions or roofs, consisting of a preformed slab comprising sheets of facing material secured at their edges to the opposite sides of stiffening strips of rigid material forming with said sheets a shallow box-like structure substantially closed on all sides, and a filling of light weight plastic heat and sound insulating material filling the space within said shallow box-like structure.

11. A substantially rigid heat and sound proof light-weight "filling-in" panel for attachment to a supporting frame in the construction of walls, partitions or roofs, consisting of a preformed slab comprising a sheet of facing material having its edges secured to and stiffened by strips of substantially rigid material, additional stiffening strip means secured to said sheet within the space defined by said edge stiffening strips and of less height than the latter, and a filling of light weight plastic heat and sound insulating material filling the space within said edge stiffening strips and embedding said additional stiffening strip means.
